CONRAD KNOTH, OF HILLSIDE, NEW JERSEY, ASSIGNOR TO GENERAL MOTORS CORPORATION, OF DETROIT, MICHIGAN, A CORPORATION OF DELAWARE

RIVETING MACHINE

Application filed October 29, 1924. Serial No. 746,500.

This invention relates to riveting machines and is herein shown as embodied in a machine for automatically riveting a circular series of tie-bars to the end rings of a roller bearing cage.

One well known form of roller bearing cage comprises opposite end rings joined and spaced by a circular series of riveted tie-bars. Hitherto, it has been the practice to place one or both of the end rings and the tie bars, in a holding ring or block and then move the block by hand to present the projecting ends of the tie bars one-by-one to a riveting tool. The operation is very fatiguing due to the vibration induced by the riveter and the operator must consequently use both hands to turn the block and hold the end ring on the tie-bars.

An object of the invention, therefore, is to provide an improved machine for heading a series of bars. Another object is to provide a machine for automatically securing a circular series of tie-bars to end rings. Another object is to eliminate or decrease the fatigue of the operator in performing this operation and to increase the output. Still another object is to provide apparatus for controlling or feeding tie-bar holders in accordance with the tie-bar spacing and to automatically stop the holder and the riveter at the end of a predetermined number of riveting operations. Yet another object is to provide improved apparatus for use in making roller bearing cages of different diameters, different lengths or cages wherein the tie-bars are differently spaced or vary in number.

To these ends and also to improve generally upon devices of the character indicated my invention consists in the various matters hereinafter described and claimed.

Figure 1 is a side elevation of the machine with some parts in section and some removed.

Figure 2 is a front elevation with some parts omitted for clearness.

Figure 3 is a plan view of the machine with some parts omitted.

Figure 4 is a side elevation of a detail.

Figure 5 is a sectional view of a first operation work holder.

Figure 6 is a detail view of a second-operation work holder.

Figure 7 is a detail view of a second-operation work holder adapted for use with a different cage.

Figure 8 is a plan view of a centering or steadyng device.

Figure 9 is a side view of the latter with parts in section.

Figure 10 is a plan view of a detail.

Referring to the drawings, the numeral 10 indicates a frame or standard to the upper end of which is fixed a frame piece or head 12 having an overhanging arm 14 which guides a reciprocating plunger 16 having a riveting tool 18 at the lower end. The plunger is operated by a lever 20 pivoted at the top of the head 12 and rapidly oscillated by connections to a horizontal shaft driven by a pulley 22. The riveting tool 18 is started and stopped by any suitable clutch control 24 actuated in one direction by a spring 26 and actuated in the other direction by a cable or chain 28 connected to the clutch control 24 and to a bracket 30.

A support 34 for the work and some of the operating mechanism is slidably mounted for vertical adjustment on ways 36 on the standard 10, and elevating screw 38 and hand wheel 40 serving to raise and lower the support. The hub of the hand wheel 40 rests on a vertical upright 42 and is grooved and retained thereon by the forked end of an angle plate 43 fastened to the upright. At the top of the support 34 is a horizontal slideway 44 having undercut edges to receive a carrier 46 which slides from front to rear of the machine. A gib 48 (Figure 2) is removably fixed to the carrier so that the latter can be easily removed from the slideway.

The center of the carrier 46 has a circular recess which rotatably carries a turntable 50 having an undercut slide or tongue 52 and a depending cylindrical extension 54 abutting against a washer 56 which is clamped between a bevel gear 60 and the cylindrical extension by a vertical stud shaft 58 having a clamping nut 62 at the upper end. The engagement of the washer 56 with the extension 54 provides a friction drive. The turntable is intermit-

tently turned to carry a circular series of rivets or tie-bars, supported in a suitable holder, beneath the riveting tool. The gear 60 meshes with a bevel gear 66 having its hub splined to the rear end of a horizontal shaft 68, said hub being rotatably mounted in a lug 70 depending from the carrier 46. The bevel gear 66 is maintained in mesh with the gear 60 by being confined between the latter and the depending lug 70 so that driving engagement is maintained in spite of front to rear movement of the carrier, as when adjusting the latter for cages of different diameters. The shaft 68 has a collar 72 at the front end to hold it against rearward movement and has keyed to it a bevel gear 74 driven by a bevel gear 76 on a vertical shaft 78 journalled in the support 34.

The vertical shaft 78 has a bevel gear 80 at its lower end driven by a bevel gear 82 on a horizontal shaft 84 journalled in the support 34 and intermittently turned by a ratchet 86 and a pawl 88 which swings with an arm 90 the hub of which loosely surrounds the shaft. When the pawl is at its forward limit of movement, it strikes against a fixed stud 92 which jams the pawl inwardly against the face 94 of the ratchet tooth, the front face of the pawl also fitting the radial face 96 of the tooth and, inasmuch as the face 94 is inclined inwardly towards the center of the ratchet, the ratchet is held positively against any further movement. As will later appear, the riveting operations are performed on different numbers of tie-bars and, accordingly, the step-by-step turning movement of the ratchet can be varied from a short feed to a longer one. A shield 98 is turnably mounted on the shaft 84 and carries a plate 100 which is designed to be placed in the path of the pawl 88 to enable the latter to feed one or more teeth as desired, the shield being slotted and having in the slot a threaded stud 102 engaged by a nut by which the shield can be clamped in the desired position. The number of teeth on the ratchet is the same as the number of tie-bars to be riveted or a multiple thereof and the shield plate 100 is used to uncover more or less teeth for feeding, depending on the number of tie-bars in the series. The ratchet is removable however and is replaceable by another having a different number of teeth if the number of tie-bars in the series to be riveted is not commensurate with the number of teeth on the first ratchet.

The arm 90 is oscillated by a link 104 which is attached at its rear end to a slide bar 106 which is slotted to embrace and be guided on a driven stub shaft 108. The stub shaft 108 is journalled in the support 34 and carries a cam 110 at the end, engaging a roller 112 on the slide bar 106, a spring 114 fixed to the support 34 and to the link 104 holding the roller against the cam. The rear of the slide bar 106 carries a right angular plate 116

which engages behind the flexible clutch controlling connection 28, above referred to, so that the movement of the ratchet mechanism controls the starting and stopping of the riveting tool. The cam 110 makes one revolution to effect each intermittent feeding movement of the ratchet and the turn table, and it starts the operation of the riveting tool at the end of each feed movement, the angular plate 116 at such times pulling on the flexible connection 28 and subsequently releasing it to stop the riveter while the next feed is taking place.

The horizontal stub shaft 108 is rotated by a worm wheel in the casing 118, said worm wheel being driven by a worm 120 keyed to a vertical shaft 122 by a spline 124, this connection providing for the driving of the worm in different vertical positions of the sliding support 34. The shaft 122 has a thrust collar 126 near the lower end and is journalled at the top in a casing 128 which houses spiral gears 130 and 132 the latter being on a horizontal driving shaft 134 driven by a pulley 136 and having a suitable clutch 138 by which it can be started and stopped. The clutch 138 is controlled by the end of a lever 140 pivoted at 142 on the frame and having its lower end slotted at 144 and pivotally connected to a link 146 having a knee pad 152 at its front end. The link has a slot 148 guided by a stud 150 on the support and also is slotted to embrace and slide on the shaft 84 above referred to. The slot 144 in the lever 140 provides for the operation of the clutch in different vertical positions of the work carrying support 34. The link 146 carries a roller 154 arranged to ride on a peripheral cam 156 fixed to the shaft 84 and intermittently turned by the ratchet mechanism. A spring 158 fixed to the link 146 and to the frame holds the roller 154 against its cam 156 and tends to make the roller ride into a recess of the cam at the end of a predetermined number of riveting operations depending on the number of teeth on the ratchet or the number of feed strokes of the pawl necessary to complete a rotation of the ratchet.

The bevel gears all have the same number of teeth so that a complete rotation of the ratchet effects a complete rotation of the turntable and the piece of work thereon. It is apparent that the riveting tool is operated a plurality of times against each rivet or tie-bar, at the end of each feeding movement, and that it is stopped while the turntable and work piece are being turned to bring another rivet or tie-bar under the tool. When the last feeding movement is completed, the recess in the cam 156 reaches the roller 154, and, in the absence of some mechanism to prevent it, the roller would ride into the recess of cam 156 and stop the rotation of shaft 134 which rotates the cam 110. Hence the riveting tool would continue to operate because 100

the cam 110 would not be turned to bring its recess opposite its roller 112 to thereby release the flexible clutch controlling connection 28. Mechanism is therefore provided to temporarily keep the roller 154 out of the recess in cam 156 so that the cam 110 will be turned far enough to allow the riveting tool to stop. This mechanism comprises a bail made in connected sections 160 and 162, the former having pins 164 extending into the hub of the pawl carrying arm 90 so that every swinging movement of the arm 90 swings the bail and causes a tail portion or arrester 166 thereon to move into the path of roller 154. Of course, all of these swinging movements are idle except the last because it is not until the last that the recess in cam 156 reaches the roller 154. Overfeeding of the turntable is further prevented by the provision of a wooden friction block 168 which is pressed by a spring 170 against the periphery of the turntable, the spring being carried in a sleeve 172 and being adjustable by means of a tapered screw plug 174.

In the operation of securing a circular series of shouldered tie-bars to the end rings of a roller bearing cage, some mechanism is needed to hold the bars and the first end ring assembled during the first riveting operation.

In Figure 1, there is shown a series of shouldered tie-bars 180 to be riveted to an end ring 182. To take the thrust of the riveting tool the shoulders at the lower ends of the tie-bars rest against a hardened plate 186 which is fastened to an apertured bar holding ring 184 by means of suitable dowel pins and screws 188. The openings in the ring 184 fit all sides of the bars and support the bars against lateral displacement during riveting. The lower reduced ends of the tie-bars, to be subsequently riveted project downwardly into holes on the plate 186. The plate 186 is held by a key 190 on a cylindrical core 192 projecting upwardly from a base plate 194 which has an annular supporting surface for the hardened plate and the bar holding ring. The base plate 194 is provided with an undercut groove 196 adapted for detachable and sliding engagement with the slide 52 on the rotatable turntable. The slide is turned to a front-to-rear position when the base plate is slid on or off. The bar holding ring 184 has an annular recess 198 which forms a shoulder engaged by a circular plate 200 clamped to the core 192 by a clamping stud 202.

The carrier 46 is slidable from front to rear on the support 34 and held in adjusted position by two spaced adjusting screws which abut against opposite sides of a lug 204 (Figure 2) on the support 34. One of these screws is indicated at 206 and is carried by a plate 208 having a tongue bolted in a longitudinal slot 209 in the side of the carrier. This adjustment is used so that, when cages of

slightly different diameter from that shown are to be operated on, the circle of the tie-bar series can be brought directly under the tool. In such cases, the bar holding ring 184 and hardened plate 186 are removed and replaced by others of the required diameter. In case of any great variation in the diameters of the cages, the base plate 194, the holding ring 184 and the plate 186 are entirely removed and replaced by others. Any small differences in the lengths of the tie-bars of different cages is compensated for by elevating or lowering the support 34 by means of the screw 38. When the tie-bars are very long and would project so far above the ring 184 that there would be danger of them buckling under riveting pressure, the ring 184 is removed and replaced by a thicker one such as shown at 184A in Figure 5.

Inasmuch as the rapid reciprocation of the riveting tool causes considerable vibration of the work, a pair of hold-downs are adjustably mounted so as to overlie the end ring 182 close to the projecting ends of the tie-bars. Each hold-down comprises a circular plate or foot 210 having an eccentric stud 212 rotatably and slidably mounted in a hollow sleeve 214 on the forward end of an arm 216 which is bolted by means of the bolts 218 to the overhanging arm 14 above described. The bolted portion of the arm 216 has an enlargement 217 fitting between the webs 220 of the overhanging arm 14 to hold the arm rigidly in place. The eccentric studs 212 are fastened in their adjusted positions by clamping screws 222 which have flattened faces engaging the shanks of the studs.

In Figure 6 there is shown a device for holding a circular series of tie-bars after they have been riveted to a first end ring and while they are being riveted to a second end ring. The first end ring 224 to which tie-bars 226 have already been fastened is arranged to rest upon a hardened plate 228 surrounding a core 230 which projects upwardly from a base plate 232. The base plate and core of the first holder, shown in Figure 5, may be used if desired. Rollers 234 of the roller bearing are first sleeved over the tie-bars and then a second end ring 236, which is to be riveted to the tie-bars, is placed over the reduced, projecting ends of the tie-bars, said rollers then fitting curved grooves 238 in a detachable sleeve 240 which surrounds the core and is connected to it by means of a key 242. The base plate 232 has an undercut groove 244 to fit the slide 52.

When the cages differ a little in diameter from that shown, the sleeve 240 is removed and replaced by another of a different thickness, the carrier 46 then being slid from front to rear as before to bring the tie-bars directly under the riveting tool. Small differences in the lengths of tie-bar series is compensated for as before, by elevating or lowering the

support 34. In case of very long tie-bar series, a longer sleeve such as shown at 246 in Figure 7 may be substituted for the sleeve 240. In case of tie-bar series of considerable difference in diameter, the base plate 232 is replaced by another of the required size. It will be noted that the first end ring 224 to which the bars 226 have been riveted acts as a bar holding ring during the operation of attaching the second end ring. The rollers 234 by extending into the grooves 238 act to key the cage to the core 230 and allow the cage to be positively rotated. This construction also properly indexes the tie-bars so that they come under the riveting tool. In the particular bearing shown, the rollers are sleeved on the tie-bars but the holder is adapted for other bearings, such as the type in which the rollers are held between opposite projections or teats on the end rings, between the tie-bars.

Mechanism is also provided to steady the rotary base plate and work holder during the riveting operation and to center the same on the turntable 50. As shown in Figures 8 and 9, two rear steadyng fingers 250 and two front steadyng fingers 252 are provided, each rear finger being longitudinally slotted to slide along a clamping stud 256 fastened to a curved bar 258 secured by bolts 260 to the carrier 46. The front fingers 252 are similarly fastened to a curved bar 262 which is pivoted at 264 to a bracket 266 fastened at one side of the carrier and having a flat face, or shelf 268 which supports the curved bar 262 when it is swung outwardly to allow one of the base plates and work holders to be installed on the turntable. The fingers are shown in their outermost positions to surround a base plate and work holder of large diameter as indicated by the dot and dash line in Figure 8. For the smaller holders, the fingers are moved radially inwards and clamped in a fixed position. The fingers merely contact lightly with the holder to steady it without interfering with its rotation. The curved bar 262 has a hardened latch plate 270 near one end adapted to be engaged by a hook 272 on a latch lever 274, pivoted at 276 between cheeks on a bracket 278, and normally pressed down to a latching position by a spring 280 housed in the bracket and engaging the short end of the latch lever. The front of the latch hook has an incline 282 to ride up over the latch plate 270 and a plug 284 backed up by a spring serves as a cushion for the curved plate when it is swung into latched position. The latch lever 274 has a lift pin 288 by which it can be lifted when swinging the curved bar 262 to one side to take off a work holder. The curved bar 262 is manipulated by a handle 286.

Although the invention has been described by reference to a specific machine, it should be understood that, in its broader aspects, the

invention is not limited to the particular machine selected for mere illustrative purposes.

I claim:

1. In apparatus of the character described, a riveting tool, means for reciprocating the tool, a movable holder for supporting a series of bars to be headed, said holder comprising a member having openings fitting all sides of the bars, and mechanism for intermittently moving the holder to bring the bars successively to the riveting tool, and means for automatically stopping the reciprocation of said riveting tool during the intermittent movement of the holder; substantially as described. 70 75 80

2. In apparatus of the character described, a riveting tool, means for reciprocating the tool, a holder for supporting a circular series of bars, mechanism for intermittently turning the holder to carry the bars successively to the riveting tool, a cam driven by said turning mechanism, and means operated by the cam for intermittently starting the tool reciprocating means; substantially as described. 85 90 95

3. In apparatus of the character described, a riveting tool, means for reciprocating the riveting tool, a clutch for controlling said means, a fixed member, a flexible connection 95 from said clutch to said fixed member, a holder for bars to be riveted, mechanism for moving said holder, and a device controlled by said mechanism for engaging said flexible connection and operating the reciprocating means; substantially as described. 100

4. In apparatus of the character described, a riveting tool, means for operating the tool, a holder for supporting a circular series of bars, mechanism for intermittently turning the holder to carry the bars successively to the riveting tool, a pair of cams driven by said turning mechanism, means controlled by one of said cams for intermittently starting the tool operating means, and means controlled by the other cam for stopping the intermittent turning movement; substantially as described. 105 110 115

5. In apparatus of the character described, a riveting tool, means for operating the tool, a holder for supporting a circular series of bars, means for intermittently turning the holder to carry the bars successively to the riveting tool, means for stopping the holder after a predetermined number of turning 120 movements, and means for stopping the operation of said riveting tool after a predetermined number of riveting operations; substantially as described. 125 130

6. In apparatus of the character described, a riveting tool, means for operating the tool, a holder for supporting a circular series of bars, means for intermittently turning the holder to carry the bars successively to the riveting tool, and means for varying the ex- 125 130

tent of said intermittent turning movement for different series of bars; substantially as described.

7. In apparatus of the character described, 5 a riveting tool, means for operating the tool, a holder for supporting a circular series of bars, mechanism, including a ratchet and pawl, for intermittently turning the holder to carry the bars successively to the riveting 10 tool, and a movable shield overlying a portion of the ratchet in the path of the pawl to vary the extent of the intermittent turning movement; substantially as described.

8. In apparatus of the character described, 15 a riveting tool, means for operating the tool, a holder for supporting a circular series of bars, means for intermittently turning the holder around an axis to carry the bars successively to the riveting tool, and means for 20 changing the position of the axis of the holder with respect to the tool; substantially as described.

9. In apparatus of the character described, 25 a riveting tool, means for operating the tool, a holder for supporting a circular series of bars, means for intermittently turning the holder to carry the bars successively to the riveting tool, and a sliding carrier for adjusting the holder transversely with respect 30 to the riveting tool; substantially as described.

10. In apparatus of the character described, 35 a riveting tool, means for operating the tool, a rotary holder for supporting a series of bars, means for intermittently turning the holder to carry the bars successively to the riveting tool, a horizontally sliding carrier for the holder, and means for changing the level of the carrier; substantially as described.

11. In apparatus of the character described, 40 a riveting tool, means for operating the tool, a rotary holder for supporting a series of bars, means for intermittently turning the holder to carry the bars successively to the riveting tool, a laterally sliding carrier for the holder, and a detachable connection between the laterally sliding carrier and the holder; substantially as described.

12. In apparatus of the character described, 45 a riveting tool, means for operating the tool, a holder for holding a circular series of bars, a turntable supporting the holder, means for intermittently rotating the turntable to carry the bars successively to the riveting tool, and a tongue on the turntable for detachably and selectively securing various holders; substantially as described.

13. In apparatus of the character described, 50 a riveting tool, means for operating the tool, a holder for supporting a circular series of bars, a turntable supporting the holder, means for intermittently rotating the turntable to carry the bars successively to the riveting tool, means on the turntable for se-

lectively securing various holders, and a laterally sliding carrier for the turn table; substantially as described.

14. In apparatus of the character described, 55 a base plate having an annular supporting surface, and a bar-holding ring for said base plate to support a series of bars, said ring being removable and replaceable by a ring of different thickness to support a series of bars of different length; substantially 60 as described.

15. In apparatus of the character described, 65 a work holding member for circular series of bars to be riveted, said member having a core, and a detachable sleeve interposed in the space between the core and a selected 70 series of bars; substantially as described.

16. In apparatus of the character described, 75 a work holding member for a series of bars to be riveted, said member comprising a base plate having a central core and an annular supporting surface, and mechanism for rotating the member; substantially as described.

17. In apparatus of the character described, 80 a work holding member for a series of bars to be riveted, said member comprising a base plate having an annular supporting surface, and a hardened ring interposed between the annular supporting surface and a circular 85 series of bars; substantially as described.

18. In apparatus of the character described, 90 a work holding member for series of bars to be riveted, said member comprising a base plate having a central core and an annular supporting surface, and a bar holding 95 ring for surrounding said core to support a circular series of bars, said bar holding ring being removable and replaceable by a ring of different thickness for supporting a circular 100 series of bars of another length; substantially as described.

19. In apparatus of the character described, 105 a work holding member for a series of bars to be riveted, said member comprising a base plate having a central core and an annular supporting surface, a sleeve interposed between the core and a circular series 110 of bars, and a ring interposed between the annular supporting surface and said series of bars; substantially as described.

20. In apparatus of the character described, 115 a work holding member for a series of bars to be riveted, said member comprising a base plate having a central core and an annular supporting surface, a bar holding ring surrounding the core and holding and spacing a circular series of said bars, and a hardened ring interposed between the annular supporting surface and the bar holding ring; 120 substantially as described.

21. In apparatus of the character described, 125 a plate having a series of openings for holding and spacing a series of shouldered tie bars, and a plate having a hardened surface 130

- to support the shoulders of said tie bars against riveting pressure; substantially as described.
22. In apparatus of the character described, a ring having a circular series of openings for holding and spacing a circular series of tie bars, a ring having a hardened surface to support said tie bars against riveting pressure, and a member having an annular surface to support said rings and a cylindrical core to center said rings; substantially as described. 70
23. In apparatus of the character described, a base plate having a central core and a flat annular face, a bar holding ring having a series of openings for the tie bars and a shouldered recess, a circular plate fitting the recess, and a clamping screw between the core and the circular plate; substantially as described. 75
24. In apparatus of the character described, a riveting tool, means for operating the tool, a work holder for a series of tie bars to be riveted to an end ring, means for rotating the work holder, and a hold-down plate at one side of the riveting tool and overlying the end ring; substantially as described. 80
25. In apparatus of the character described, a riveting tool, means for operating the tool, a work holder for a series of tie bars to be riveted to an end ring, means for rotating the work holder, a hold-down plate at one side of the riveting tool and overlying the end ring, and means for fixing the plate in different positions in a horizontal plane; substantially as described. 85
26. In apparatus of the character described, a riveting tool, means for operating the tool, a work holder for a series of tie bars to be riveted to an end ring, means for rotating the work holder, a hold-down plate having an eccentric stud, and means for clamping the stud in different angular positions; substantially as described. 90
27. In apparatus of the character described, a riveting tool, means for operating the tool, a work holder for a series of tie bars to be riveted to an end ring, means for rotating the work holder, a hold-down plate at one side of the riveting tool and overlying the end ring, said plate having an eccentric stud, a supporting arm rotatably and slidably carrying the stud, and means for clamping the stud in different angular positions and at different levels; substantially as described. 95
28. In apparatus of the character described, a riveting tool, means for operating the tool, and mechanism for presenting a circular series of tie bars successively to the tool, said mechanism comprising a slidable base plate, a turn table supporting the base plate, and a plurality of holding fingers radially adjustable towards and from the base plate to center the latter on the turn table; substantially as described. 100
29. In apparatus of the character described, a riveting tool, means for operating the tool, and mechanism for presenting a circular series of tie bars successively to the tool, said mechanism comprising a slidable base plate, means for slidably supporting the base plate, a pair of holding fingers at one side of the base plate, and a swinging carrier for other holding fingers at the other side of the base plate; substantially as described. 105
30. In apparatus of the character described, a riveting tool, means for operating the tool, and mechanism for presenting a circular series of tie bars successively to the tool, said mechanism comprising a slidable base plate, means for slidably supporting the base plate, a pair of holding fingers at one side of the base plate, and a swinging carrier for other holding fingers at the other side of the base plate, and a latch for holding and releasing the swinging carrier; substantially as described. 110
- In testimony whereof I hereunto affix my signature.
- CONRAD KNOTH. 115
